UNITED STATES PATENT OFFICE.

JACK GREEN, OF NORFOLK, VIRGINIA.

CLEANING APPARATUS.

Application filed May 18, 1926. Serial No. 109,957.

This invention relates to an improvement in cleaning apparatus designed more particularly for cleaning the interior of metal containers.

5 The main object of the present invention is the provision of a portable apparatus, in which containers may be removably fixed, and while fixed in such apparatus, subjected to a movement in several directions to insure that the cleaning element introduced into the container, whether the conventional chains, or a cleansing fluid, or both, may effectively search all interior parts of the container for a thorough cleansing thereof.

10 15 The invention comprehends a readily portable frame supporting a semi-cylindrical cradle mounted in the frame for manual rocking or rotation, with means carried by the cradle whereby containers of various sizes may be fixed therein. The frame is supported upon rockers having resilient cushioning means to induce an endwise rocking movement of the cradle and thereby of the container during the cleaning operation.

20 25 The invention is illustrated in the accompanying drawings, in which:

Fig. 1 is a view in side elevation of the improved cleaning apparatus, a container being shown fixed therein.

30 Fig. 2 is an end view of the same.

Fig. 3 is a transverse section, showing particularly the means for securing the containers in the cradles.

35 Fig. 4 is a sectional detail showing the means for connecting the chains in the bung hole of the container.

The improved apparatus comprises a frame including skeleton uprights 1, connected in spaced rigid relation by cross braces 2 and bottom braces 3. A cradle 4 is mounted for rotation on and supported between the uprights 1, this cradle comprising a curved bottom wall 5, of less than full semi-circular length transversely, and end walls 6 which extend above the edge margins of the bottom wall. The end walls are provided with trunnions 7 mounted in bearings 8 on the upper ends of the uprights 1, and one of the trunnions is extended beyond the bearing and provided with a pinion 10 to be engaged by a gear 11 having bearing in a bracket 12 rising from the adjacent upright, with the shaft of the gear connected to a handle 13, whereby the cradle may be rocked or rotated at will in an obvious manner.

The container, here shown as a metal container 14, is adapted to be placed in the cradle and more or less rigidly secured therein by means illustrated particularly in Fig. 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540

Obviously, with the container in place in the cradle, the chain 15 may be tightened about the container and engaged with the hook end of the lever, following which the free end of the arm 20 of the lever may be drawn downwardly by a pull on the chain connector 21 and the latter secured to the fastening 22. The container is thus secured in the cradle in a manner to permit its convenient removal, it being apparent that the fastening means will readily accommodate containers of different diameters.

The uprights 1 are preferably extended laterally at their lower ends as at 23, and these lateral extensions are connected to rockers 24 adapted to rest upon the floor or other surface indicated at 25. The ends of the rockers have spring pressed pins 26 depending therefrom acting to cushion and assist in the rocking movement in an obvious manner.

In order to provide for conveniently applying the containers to the cradle or for conveniently removing the containers therefrom, it is proposed to rock the cradle to a receiving or discharging position, that is, with one edge thereof in substantially the lowermost position and to lock the same in such position. For this purpose, I provide on one of the uprights of the frame a bracket 31 forming with the frame a staple-like member to receive a pin 32, the end wall 6

of the rocker being formed with an opening 33, into which the pin may be inserted to thus hold the rocker in receiving or discharging position. A portable skid may be used up which the containers may be rolled for delivery to the cradle after the cradle has been held in the position referred to. The cradle proper is preferably formed with a central opening 34 and the cradle may be 10 slightly concaved so as to accommodate casks or bilge barrels with a more or less interfit, while for better retaining metal containers, which are uniformly of even diameter throughout their lengths, the wall of the 15 cradle is provided at appropriate points with lugs 35, which are so positioned as to rest beyond the usual reinforcing bars or hoops 36 of the container to prevent longitudinal movement thereof.

20 If desired, and as preferred, a series of chains 27 may be loosely placed in the container 14 for the cleaning function. Preferably these chains are secured to an eye 28 forming part of a closure 29 adapted to be 25 screwed or otherwise held in the usual bung opening 30 of the container 14. Obviously, a cleansing fluid of any appropriate material or materials may be used in the container with or without the chains.

30 As constructed, the operator by suitably manipulating the handle 13 may impart a rocking or revolving movement to the container and at the same time cause a rocking of the entire structure longitudinally on 35 rockers 24. This movement will insure a proper searching action of the chains, cleansing fluid, or both, with the effect to thoroughly cleanse the full interior surface of the container.

40 It is to be particularly noted that the apparatus is a portable one and may be readily moved from place to place; and that the cradle may be readily positioned with one or the other of its edges in a lowermost position so that the container may be readily 45 rolled therein by a single operator. Furthermore, after the cleaning operation is completed, a release of the fastening means will permit the container to be self-discharged from the cradle by merely tilting the latter to permit a gravitational movement of the container.

50 It is to be particularly noted that the play of the chains in the cask barrel or container may be through the full sweep of the in-

terior by rotating the cradle or may be concentrated on a particular length or portion of the container by a comparatively slight rocking movement of the cradle. Thus if the container or cask has a particular spot requiring more cleaning than the remainder of the interior, such spot or spots may be operated on directly until cleaned by appropriate operation of the cradle.

What I claim is:

1. A portable cleaning apparatus, including rockers, frame uprights extending transversely of and connected to said rockers, a cradle mounted for movement between the upright, the axial line of the cradle extending longitudinally of the rockers, a fastening plate hinged to one marginal edge of the cradle, a fastening chain secured to the other marginal edge of the cradle, a lever carried by said plate and having a hook end to be 75 engaged by said chain, a connector extending from the lever, and a connector holding means mounted on said plate.

2. A portable cleaning apparatus including frame uprights, a cradle mounted for 80 rotating movement between the uprights, and means secured to the opposing edges of the cradle to overlie and engage a container resting in the cradle, said means including a fastening plate movably connected to one 85 edge of the cradle and adapted to bear on the periphery of the container above the cradle, a flexible connection between said plate and the opposite edge of the cradle, and means for tightening such connection. 90

3. A portable cleaning apparatus including frame uprights, a cradle mounted for rotative movement between the uprights, and a fastening means for securing a container within the cradle, said fastening means including a chain connected to one edge of the cradle and a lever having means for connection with the opposite edge of the cradle, said lever being formed on one side of its fulcrum with means to engage any link of 100 the chain, and means whereby the end of the lever on the opposite side of the fulcrum may be fixed in position to exert endwise strain on the chain to thereby secure the container within the cradle, the said fixing means being releasable at will to permit the lever to move about its pivot to release the 105 tension on the chain.

In testimony whereof I affix my signature.
JACK GREEN. [L.S.]
